PROCESS OF MAKING MATCHES

Filed Jan. 10, 1930

UNITED STATES PATENT OFFICE

CLARE K. LIGHT, OF OSWEGO, NEW YORK, ASSIGNOR TO THE DIAMOND MATCH COMPANY, OF CHICAGO, ILLINOIS, A CORPORATION OF ILLINOIS

PROCESS OF MAKING MATCHES

Application filed January 10, 1930. Serial No. 413,822.

This invention relates to a process of making matches having splints of permeable combustible material; its object being to provide for the economical and efficient treatment of 5 the match splints with material which is effective to limit the flame to a relatively small portion of the splint when a match is ignited, and also with material which is effective to prevent the glowing of the burnt or charred 10 part of the splint when the flame is extinguished.

The invention is especially designed for use in connection with a match making machine wherein the splints are inserted endwise, row 15 by row, in an endless carrier and thereby rigidly held in spaced parallel relation and transported through the match making path, including wax (as paraffin) and match composition applying mechanisms.

20 In carrying out the invention in the preferred way the match splints, projecting from and supported in spaced parallel relation by the carrier, are treated with a material which permits the burning of the splints when they 25 are ignited yet prevents their glowing when the flame is extinguished. This anti-glow material preferably consists of an ammonium phosphate solution with which the splints are impregnated, or of powdered ammonium 30 phosphate with which the exposed surfaces of the splints are dusted or coated. The free end portions of the impregnated splints or the coated splints are dipped to a suitable depth into molten wax, as paraffin, and they 35 are then exposed to the atmosphere for a brief interval of time to allow the wax to set. This done, the splints are sprayed with a solution of material, such as ammonium phosphate which impregnates and renders practically 40 fire-proof the portions of the splints above the waxed or paraffined portions, yet does not accumulate upon or impair the efficient burning quality of such paraffined portions.

The free extremities of the paraffined portions of the splints are tipped with any usual or approved ignitable composition or compositions to form the match heads, whereupon the matches are conveyed through a suitable drying space, whence they are discharged 50 from the carrier and packed.

In the drawing; which is a diagram of parts of a match making machine designed to carry out my hereinbefore described process, 1 designates a portion of an endless carrier in which match splints, 2, are endwise 55 inserted, row by row, and thereby rigidly held in spaced parallel relation. The type of machine illustrated embodies a cutter head 3 having instrumentalities whereby succeeding rows of splints are cut from a block of wood 60 and forcibly inserted in perforations in the carrier.

4 designates a sprayer located adjacent the cutter head and adapted to project upon and longitudinally of the splints borne by the 65 carrier a fine spray or mist of material effective to prevent the glowing of the splint material when a match has been ignited and the flame extinguished. This material is preferably a concentrated solution of phosphate 70 ammonium, about 3.5 Baumé, which is quickly absorbed by the splints; but, if desired, the material may comprise pulverized phosphate of ammonium which in a dry state adheres to and forms a light dust or coating on 75 the exposed surfaces of the splints.

5 designates a bath of molten paraffin, or the like, in which the lower ends of the depending splints, after they leave the sprayer, are immersed to a depth corresponding with 80 the desired inflammable area of the splints. If desired a suitable heater may be interposed between the sprayer and the paraffin bath, in order to ensure the drying of the wet impregnated splints before they are dipped in the 85 bath.

6 designates a second sprayer arranged adjacent the path of the splints, and sufficiently distant from the paraffin bath to allow the paraffin on the splints to set or harden before 90 the splints reach the second sprayer. This second sprayer functions to project upon and longitudinally of the splints adjacent thereto a fine spray or mist of a solution effective to impregnate the exposed unparaffined portion of each individual splint and render it sufficiently fire-resistant to limit the flame to the paraffined portion of the splint when the match is ignited. The impregnating material is preferably a concentrated solution of 95 100

phosphate ammonium, about 21.5 Baumé, the velocity of which as it is projected in a fine spray along the water repellent paraffined portion of the splint prevents its adherence to or accumulation on the paraffined surface. Consequently the efficient burning quality of the paraffined portions of the splints is unimpaired.

7 designates a composition containing vat 10 equipped with a transfer roll 8 by means of which match head composition is applied to the lower paraffined ends of the depending splints after the splints leave the second sprayer.

15 I claim—

1. A process of making matches, comprising treating a splint of permeable combustible material with an anti-glowing material, treating a predetermined inflammable area 20 of the splint with wax, projecting a fine spray or mist of a solution of fire-resistant material upon and lengthwise of the waxed and unwaxed portions of the splint in such manner that the solution passes to and impregnates 25 the unwaxed portion of the splint without its accumulating on or impairing the burning quality of the waxed portion, and applying match head composition to the free end of the waxed portion.

30 2. In a process of making matches whereof the splints have waxed and unwaxed portions, the step of impregnating the unwaxed portions of the splints with fire-resistant material, comprising projecting a fine spray or 35 mist of a solution of such material upon and lengthwise of the waxed and unwaxed portions of the individual splints in such manner that the solution passes to and impregnates the unwaxed portion of each splint without 40 its accumulating on or impairing the burning quality of the waxed portion of the splint.

3. A process of making matches, comprising 45 impregnating spaced apart rows of splints of combustible permeable material with a solution of phosphate ammonium, about 3.5 Baumé, treating a predetermined inflammable area of each individual splint with wax, projecting a fine spray or mist of a 50 solution of phosphate ammonium about 21.5 Baumé, upon and lengthwise of the waxed portion of the splint whereby such spray passes to and impregnates the unwaxed portion of the splint without its accumulating on or 55 impairing the burning quality of the waxed portion, and applying match head composition to the free end of the waxed portion.

4. A process of treating rows of spaced 60 apart match splints which are each held at one end in and project from a suitable carrier, comprising treating the exposed surfaces of the respective splints with an anti-glowing material, treating the free end portions of the 65 said splints with wax, projecting a fine spray or mist of a solution of fire-resistant material

upon and lengthwise of the waxed and unwaxed portions of the respective splints without its accumulating on or impairing the burning quality of the waxed portions, and applying match head composition to the free 70 ends of the said waxed portions.

Signed at Oswego, in the county of Oswego and State of New York, this 7th day of January, A. D. 1930.
